UNITED STATES PATENT OFFICE

JOHN LOUIS REYNOLDS, OF LONG ISLAND CITY, NEW YORK, ASSIGNOR, BY MESNE ASSIGNMENTS, TO ELECTRICAL RESEARCH PRODUCTS INC., A CORPORATION OF DELAWARE

ELECTRICAL CONTROL SYSTEM

Application filed April 1, 1927. Serial No. 180,327.

This invention relates to control systems, and with particularity to methods and means for controlling the proper timing of sequential operations in combined sound and picture reproducing systems.

An object of the invention relates to a synchronized sound and picture reproducing system wherein a moving picture film serves as a means for controlling either automatically or through the intermediary of an attendant, the various switching operations which are incident to systems of this character.

A feature of the invention pertains to a novel form of moving picture film which is so prepared as to bear characteristics which may be availed of to effect certain mechanical operations, these characteristics being distinct from the picture portion of the film proper. These characteristics may appear in the form of a narrowing or widening of the film at the desired points or as variations in the light transmission qualities of the film.

Another feature of the invention pertains to the combination of means including a light-sensitive element for enabling a moving picture film to act as its own "cue-sheet" without the employment of mechanically acting circuit-breaking elements in close proximity to the film.

A still further feature is concerned with the combination of a "self-cued" moving picture film and a step-by-step switch for automatically controlling sequential operations.

Other features and advantages of the invention will become apparent after a consideration of the descriptions given herein-after and as pointed out in the appended claims.

Fig. 1 of the drawings shows a moving picture film prepared according to the invention with a light sensitive device or inertialess relay and associated signaling apparatus.

Fig. 2 shows a modification of the circuits and apparatus illustrated in Fig. 1

using a step-by-step switch to sequentially operate a number of separate signal devices.

Fig. 3 illustrates the manner in which the apparatus disclosed in Fig. 1, may be incorporated in any well-known form of moving picture projecting machine.

Fig. 4 shows the invention applied to a synchronized sound and picture projecting system wherein the operations are performed entirely automatically.

Referring to Figs. 1 and 3 of the drawings, there is shown a moving picture film 1 which may be of standard width, and provided with the sprocket holes 3 on either side at a distance from the edge of the film. The blank portion of the film between the feed-holes and the edge is employed to carry the "cue" marks 4, 5, 6, etc. These marks may consist of opaque strips of any suitable opaque material fastened at the proper points along the edge of the film, or they may consist of opaque portions of the film itself. These opaque strips are disposed on the film at such points as correspond to the instants at which certain sequential switching operations are to be performed.

For the purpose of guiding the film and exposing only the edge thereof to the lamp 9, there is provided a channel plate 7 having a small opening 8 therein which registers with the marks 4, 5, etc. Light from the lamp 9 is focussed by means of an appropriate optical system represented by lens 10, upon opening 8 and upon the edge of the film. This light after passing through the film is focussed by the lens 11 upon the cathode 14 of photoelectric cell 12 thus reducing the negative potential on the grid 15 of the space discharge amplifier A', which negative potential may be adjusted by means of the polarizing battery 16. Current thus flows in the plate circuit of the amplifier sufficiently to operate relay 17 which remains operated so long as cell 12 is illuminated from source 9.

When an opaque portion of the film edge 90

such as the portion 4, is presented before the opening 8, light is momentarily cut off from the cell 12 resulting in a decrease of current in the plate circuit of the amplifier and the 5 release of relay 17. Relay 17 immediately closes a circuit through the signal device 24 which may take the form of a buzzer, a lamp, or both. This signal attracts the attention of the attendant who is thereby notified 10 that a certain operation requires performing. When the opaque portion 4 passes beyond the aperture 8 the cell 12 is again illuminated and relay 17 re-operates, opening the circuit of device 24. The film advances and presents other opaque portions such as 5, to cut 15 off the light from cell 12 and relay 17 is again released to re-operate the signal device 24 indicating to the attendant that another operation is required.

20 Referring to Fig. 2 there is shown a modification of the apparatus disclosed in Fig. 1. In this figure the circuit for controlling the signal device or devices is closed mechanically by the film itself. For this purpose the 25 film 1 is notched at the points corresponding to the opaque portions 4, 5, 6, etc. of Fig. 1. Suitably mounted on the right hand edge of the guiding channel plate 6, is the spring roller 31, which normally bears against the 30 edge of film 1. Assuming the film to be moving in the direction indicated by the arrow, when a notch appears, the spring roller 31 moves to the left and closes a circuit through the contacts 38 and the winding of relay 33 which thereupon operates and 35 at its contacts 36 completes the circuit for the signal device 37 which in this instance may take the form of a buzzer or bell, for the purpose of warning the attendant that 40 a certain operation is in order. Stepping magnet 41 of switch S receives an impulse in parallel with relay 33 and attracts and releases its armature 42 to advance brush 43 from normal contact N to contact 44. It will 45 be noted that the normal position of the switch S is with the brush 43 engaging contact N or any of the contacts N₁, N₂. When brush 43 moves to contact 44 a circuit is 50 closed from the positive pole of battery 40, winding of relay 48, contact 44, brush 43, segment 49 to the negative pole of the battery. Relay 48 thus remains operated so long as brush 43 is in contact with terminal 44, and at its right-hand contact closes the 55 circuit of the white lamp W which is a characteristic signal to the attendant that a certain sequential switching operation is required.

When brush 43 is advanced to engage contact 45, due to the appearance of another notch before roller 31, relay 48 releases and 60 relay 50 operates over an obvious circuit, to close the circuit of the red lamp R which serves as a characteristic signal to the attendant 65 that another operation is in order. The

film 1 continues to advance until the next notch engages the roller 31 whereupon the brush 43 is advanced to contact 53 to close the circuit for relay 51 and green lamp G which may serve as another characteristic 70 warning to the attendant, for example that there are "two minutes to go" before the next operation is required. At the end of this warning period another notch engages roller 31 and advances brush 43 to contact 54 whereupon relay 52 operates and lights blue lamp B as an indication to the attendant that another operation in the sequence is to be performed.

Referring to Fig. 4 a description will now be given of the manner of employing the invention in one form of synchronized sound and picture projecting system whereby the switching operations are automatically performed. M and M₁ represent, schematically, 80 motors of any suitable type for driving the associated picture projecting machines P and P₁ respectively as well as the associated phonograph turntables T and T₁. It will be assumed that the first portion of the program 85 is carried by the disc 55, the sound record in which is to be reproduced in synchronism with the picture projected from the machine P, with the reproducing stylus 56 in contact with disc 55, and brush 60 of control switch S resting on the upper normal contact N. To start, the operator manipulates key 61 momentarily to energize and de-energize the stepping magnet 62 which attracts and retracts its armature 63 to step brush 60 on to contact 64. A circuit is thereupon completed from the negative pole of battery 65, left winding of relay 71, contact 64, brush 60, segment 67 to the positive pole of battery. Relay 71 at its outer right-hand contact closes 90 the circuit for motor M which drives both the phonograph turn table T and the moving picture projector P. Relay 71 upon energization locks through its right-hand winding and inner right-hand armature and the back contact of relay 88 to the positive pole of battery. This locking circuit is maintained as long as 95 relay 88 remains normal. The picture projector P and the associated phonograph reproducer are now in operation. It should 100 be noted that 73 represents schematically that portion of the projector which contains apparatus similar to that represented in Fig. 1 to the left of the dotted line. The rectangle A₁ represents the corresponding amplifier A' 105 of Fig. 1. In this case, however, instead of the contacts of relay 17 being connected to the signal device 24 they are connected to the winding of magnet 62. The film 1 passing 110 through the projector P has its edge near the beginning of the film darkened in the manner described in connection with Fig. 1 and when an opaque portion 4 is presented to the light, magnet 62 receives an impulse of current in the manner hereinbefore described 115 120

and advances brush 60 to terminal 69 whereby relay 84 is energized to light signal 85.

The lighting of the signal 85 informs the attendant that the driving motor for the projector and phonograph has started operation and that the switching network or "fader" AL is to be put into operation. When the next opaque portion of the film is reached stepping magnet 62 receives another impulse 10 of current to advance brush 60 into engagement with contact 70 whereupon a circuit for relay 66 is completed. Relay 66 upon energization closes the circuit of motor M₂ which is connected by means of suitable gearing to 15 a spindle 58 which carries the brushes 59 and 68 of the switch S₁. These brushes are thereupon rotated in a clockwise direction to reduce the number of sections of the artificial line AL in circuit with the phonograph 20 producer 57 and the amplifier A whose output circuit is connected to the loud speaker L. When the brushes 59 and 68 have reached the proper predetermined point so that the loud speaker is operating at a volume suitable 25 to the requirements of the music, which point has been previously predetermined for the guidance of the operator, the key 61 is momentarily depressed to advance brush 60 into contact with terminal 91. The stepping of the 30 switch from terminal 70 releases relay 66 and stops the motor M₂ with the brushes 59 and 68 in correct position.

With the switch S₁ properly adjusted sound is transmitted from the loud speaker. 35 The turn table was previously in operation and the stylus 56 follows the varying amplitude of the sound groove in disc 55 and causes correspondingly modulated currents to be generated by the device 57. These currents 40 are impressed upon the upper terminals of the artificial line or "fader" AL after passing through so-called "padding" sections as described in my copending application, Serial No. 180,323, filed April 1, 1927. These currents 45 are then amplified without distortion by the amplifier A before reaching the loud speaker L.

Returning now to the operation of the switching device S it should be noted that 50 when brush 60 engages terminal 91 a circuit for relay 92 is completed. This relay upon energization operates magnet 93 to cause the shutter 95 to clear the projector. Relay 92 at its inner right armature completes a locking 55 circuit for itself through the left armature of relay 72 to the positive pole of battery. Further progress of the film causes another 60 impulse to be sent to magnet 62 which steps the switch arm 60 into engagement with terminal N₁ in which position the switch remains until the film nears the completion of its travel.

When the film passing through the projector P approaches its end an impulse is sent 65 to switch 62 in the manner previously de-

scribed to advance brush 60 into engagement with terminal 79. As a result relay 72 is operated and motor M₁ is started into operation. When relay 72 operates it opens the locking circuit of relay 92 previously traced and relay 92 deenergizes allowing relay 72 to lock up 70 through its inner right armature and the left armature and back contact of relay 92 to the positive pole of battery. The release of relay 92 causes the shutter 95 to shut off the picture from the screen. The turn table T₁ and projector P₁ have now been started into operation and when the second film sends an impulse to magnet 62 the switch arm 60 is advanced into engagement with terminal 83 75 whereupon relay 84 is energized to display signal 85 to warn the attendant that the "fader" is about to be operated. The next impulse from the film advances brush 60 into engagement with terminal 86 whereupon relay 80 is energized to put into operation motor M₃. Switch S₁ is then operated in a counter-clockwise direction to gradually reduce the number of sections of line AL in circuit with reproducer 57 for the purpose of 80 gradually switching the loud speaker L from one reproducer to the other as described in my application, Serial No. 180,323, hereinbefore referred to. The attendant as before observes 85 the progress of switch S₁ and when it reaches the proper setting depresses key 61 to cause the advance of brush 60 into engagement with terminal 87. A circuit for relay 88 is thereupon completed. Relay 88 at its outer right-hand armature energizes magnet 94 to withdraw the shutter from the projector path and allow the picture to be displayed. At its left armature relay 88 opens the locking circuit of relay 71 which deenergizes and opens 90 the driving circuit of motor M bringing the first projector and turn table to rest. Relay 88 then locks through its right winding and inner right armature and the left-hand back contact of relay 71 to the positive pole of battery. A subsequent impulse from the film 95 advances brush 60 into engagement with terminal M₂.

When the film passing through projector P₁ nears the end of its run it will cause the 100 advance of switch 60 to control automatic switching operations in an identical manner to that just described. During the operation of the second turn table and projector the attendant has replaced record 55 by the record next in order and has placed a new film 105 in projector P. He now has no further duties until the first machine is again put into operation at which time he will receive the warning signal which will enable him to observe 110 the setting of the "fader".

It is immaterial which projector and turntable is first used, as it is obvious that they are used alternately and the switching operations are identical in each case.

While Fig. 4 shows all the switching move- 115

ments performed automatically, it is understood that some may be performed by the attendant. For example, instead of relays 66 and 80 operating motors M2, M3, they may light characteristically colored lamps at the proper times calling the attention of the attendant to the requirement of adjusting the "fader" brushes preparatory to switchover. Various other modifications may be made in the drawings without departing from the spirit and scope of the invention. For example instead of a single opaque strip for controlling each signal as in Fig. 2 these "cues" may take the form of a voice record of directions on the edge of the film at the proper points, and the relay 17 of Fig. 1 may be a monitoring loudspeaker so that at the proper times these directions may be reproduced and anyone may perform the required switching operations guided by these directions. The manner of producing these voice records on the same film as the moving picture forms no part of the present invention and is well-known in the art. Furthermore, the invention contemplates the use of photographic sound records which are run synchronously with the picture either as a result of being incorporated in the same film or by means of a separate machine run synchronously with the picture projector as is known to the art.

What is claimed is:

1. In a synchronized sound and motion picture projecting system, a sound reproducer, a plurality of devices for producing sound modulated currents, means comprising an adjustable current attenuating network for associating said devices with said reproducer, a motion picture projecting machine, a motion picture film embodying a control record along its length, means comprising an inertialess relay controlled by said control record on the film when passing through said projecting machine, and means controlled by said relay for effecting the automatic adjustment of said network to switch said reproducer from one to another of said devices.
2. In a synchronized sound and motion picture projecting system, a loudspeaker a first sound reproducing phonograph and a turntable therefor, a second reproducing phonograph and a turntable therefor, a motor for driving each turntable, a motion picture projector associated with each of said phonographs, an electrical current attenuating network adapted to be adjusted to associate the second phonograph with said loudspeaker when the record on the first phonograph is about to be concluded, a motion picture film embodying a control record along its length and means controlled by said control record on the film in the projector associated with said first phonograph effective when the record on the associated phonograph is about to be concluded for automatically starting the motor for the second phonograph said means

being again operated by said control record at a definite predetermined time later to vary said network.

3. In combination, a first phonograph turntable, a second phonograph turntable, a motor for each turntable, a sound reproducer, a rotary switch adapted in its movement to transfer the control of said reproducer from one to the other of said phonographs, two motors for selectively rotating said switch in either direction, a moving picture projector, a motion picture film embodying a control record along its length and means controlled by said control record on the film passing through said projector for selectively and automatically operating any of said motors at predetermined time intervals.

4. In a synchronized sound and motion picture projecting machine, a sound reproducer, a plurality of sound transmitters, a motion picture projecting machine, a motion picture film embodying a control record along its length and a switching device controlled from said control record on said film passing through said projecting machine to attenuate progressively the currents from one transmitter to the selected minimum energy level and then progressively increase the currents from the other transmitter to any desired level.

5. In a synchronized sound and motion picture projecting system, a sound reproducer, a plurality of sound transmitters, a motion picture projecting machine, a motion picture film embodying a control record along its length, an adjustable attenuating network, and means controlled by said control record on said film passing through said projecting machine to control said network to select any one of said transmitters to affect said sound reproducer.

6. In a synchronized sound and motion picture projecting machine, a sound reproducer, a plurality of sound transmitters, a motion picture projecting machine, a motion picture film embodying a control record along its length and a switching device controlled from said control record on said film passing through said projecting machine to attenuate progressively the currents from one transmitter to a selected minimum energy level, then progressively increase the currents from the other transmitter to any desired level, a signal, and means also controlled from said control record on said film for operating said signal to apprise an attendant that said switching device is to be operated.

7. In a synchronized sound and motion picture projecting machine, a sound reproducer, a plurality of sound transmitters, a motion picture projecting machine, a motion picture film embodying a control record along its length and a switching device controlled from said control record on said film passing through said projecting machine to attenuate

progressively the currents from one transmitter to a selected minimum energy level, then progressively increase the currents from the other transmitter to any desired level, a signal, means also controlled from said control record on said film for operating said signal to apprise an attendant that said switching device is to be operated, and means controllable by said attendant to control the extent of movement of said switching device.

In testimony whereof, I have signed my name to this specification, this 18th day of March, 1927.

J. LOUIS REYNOLDS.
